UNITED STATES PATENT OFFICE.

CLEMENT BROWN, OF BIRMINGHAM, ENGLAND.

CARBURETOR FOR INTERNAL-COMBUSTION ENGINES.

Application filed August 29, 1916. Serial No. 117,506.

To all whom it may concern:

Be it known that I, CLEMENT BROWN, a subject of the Kingdom of Great Britain, residing at 53 Bayswater Road, Birchfield,

- 5 Birmingham, in the county of Warwick, England, have invented certain new and useful Improvements in or Relating to Carburetors for Internal-Combustion Engines, of which the following is a specification.
- 10 The invention relates to carburetors for internal combustion engines, and particularly to that type of carburetors in which the jets for the egress of the fuel are submerged or below the normal liquid level in the sup-
- 15 ply or float chamber.

Carburetors with submerged jets are known in which the jets are in communication with the supply or float chamber and wholly subject to the influence of the suction created by the engine piston. The jet having an orifice of sufficient size to give the correct amount of fuel at low engine speeds feeds too much fuel at high engine speeds. To remedy this defect a second jet is provided which acts in supplementary capacity to the first jet, equipped with a small orifice to limit the amount of fuel fed and having and air tube opening into the communication with the supply, whereby the jet is made independent of the suction created by the engine and permits fuel to flow slowly under gravity.

It is therefore an object of the invention to provide a carburetor in which a single jet is arranged, feeding into the main air passage of the carburetor and adapted to admit a variable quantity of fuel in accordance with the operating conditions of the engine.

It is a further object of the invention to provide with a jet with an atmospheric vent in the form of a conduit communicating, at the lower end, with a space above the jet and at the upper end with the atmosphere, the opening leading to the atmosphere being suitably restricted. Upon starting the suction set up by the engine will extract at first the accumulated liquid fuel above the jet and afterwards continues to extract the liquid fuel, but now from the jet which is then submerged. At this time the full suction effect does not act on the jet, but only a part thereof, as the air inlet of the jet partly neutralizes the suction effect of the engine.

It is a further object of the invention to

provide a pilot jet with an air inlet having a restricted opening so as to partly neutralize the suction effect of the engine and thereby admit variable fuel quantities.

To the accomplishment of these and related ends, the preferred embodiments of the invention comprise the means described in the following specification, particularly pointed out in the claims forming a part thereof and illustrated in the accompanying drawings which disclose, however, but several of the embodiments which are predicated on the principle of the invention.

In said drawings:

Fig. 1 is a sectional plan view of one form of carburetor constructed in accordance with the invention;

Fig. 1^a is a diagrammatic view to illustrate the action of the improved carburetor;

Fig. 2 is a rear sectional elevation of the carburetor shown in Fig. 1, the section being taken on the line 1—2 of Fig. 1;

Figs. 3, 4, and 5 show partial sections, similar to Fig. 2 of modified forms of the invention.

Fig. 3^a is a diagrammatic view based on the parts shown in Fig. 3;

Fig. 4^a is a diagrammatic view based on the parts shown in Fig. 4;

Fig. 5^a is a diagrammatic view based on the parts shown in Fig. 5, and

Fig. 6 shows certain details referred to in connection with Fig. 5.

Referring to the drawings, and particularly to Figs. 1, 2 and 1^a, the improved carburetor has a straight air passage *a* and a main fuel inlet *b* which opens into the air passage *a* at the throat of the Venturi tube *c*, *d*. At a suitable distance from the inlet *b* a throttle member *e* is arranged and adapted to close or substantially close the main air passage. The carburetor is equipped with a pilot jet *f* communicating with the passage *a* at a point in the vicinity of the throttle *e* so that when the latter is nearly closed an excessive draft is created in the vicinity of the pilot jet. A main jet *g* is disposed below the normal level of liquid fuel in the float chamber *h*, (as indicated in the several figures by dash and dotted lines) constituting a so-called submerged jet, and communicating with the main fuel inlet *b*. An air conduit *i* communicates at its upper extremity with the atmosphere at a position above the normal

liquid fuel level in the float chamber h , and the lower extremity of said air conduit is in communication with the space above the main jet g (Fig. 2).

- 5 A conduit j opens into the space above the main jet g and leads to a space below a pilot jet k arranged in the pilot fuel conduit l , which leads to the pilot jet f . The space above the pilot jet k has an atmospheric vent by a conduit m which, at the upper end, is suitably restricted by a nipple similar to the kind shown at the top of conduit i^2 in Fig. 4, and which, at the lower end, terminates in the space above 10 the pilot jet k and below the normal liquid level. The capacity of the inlet of the air conduit m may be suitably adjusted by means of interchangeable nipples, such as shown at the top of the conduit i^2 in Fig. 4. 15 The arrangement of the parts is such that when the engine is stationary, fuel will stand above the main jet g and in the air conduit i , in the conduit j , in the space above the pilot jet k and in the air conduit m the level 20 being indicated by dash and dotted lines in Fig. 2.

The diagrammatic view shown in Fig. 1^a discloses in a simplified manner the arrangement and communication of the several jets and conduits and also discloses the level of fuel. It is clear from this diagrammatic view that the various conduits which are placed in communication will be filled with fuel when the engine is stationary, which 35 fuel is above the jets g and k and will also accumulate in the air conduits i and m , which respectively communicate with the spaces above the main jet g and above the pilot jet k . Upon starting of the engine, at 40 first, the liquid fuel accumulated above the jets will be extracted, causing the latter to rush into the main air passage of the carburetor. However, as soon as the fuel above the jets is withdrawn in the continued operation of the engine, further fuel 45 is extracted from the jets but at a more moderate rate by reason of the presence of the air inlets i and m , which communicate with the jets and partly neutralize the suction 50 effect exercised by the engine.

When the throttle e is in nearly closed position there is greater suction in the main air passage a at the region of f than at the region of b , so that all the fuel passes 55 through f . When, however, the throttle is fully open the liquid fuel is taken entirely from the main jet b and no fuel passes through f as the suction is now greater at b than at f . The arrangement is such that 60 so long as the negative pressure in the vicinity of the main fuel inlet b is sufficient to extract liquid from the main jet, the pilot jet automatically remains out of action, but as soon as the throttle is so far closed that 65 the suction in the vicinity of the main jet

is insufficient to extract fuel therefrom, the fuel is taken entirely from the pilot jet.

In the modified embodiment of the present invention, as shown in Fig. 3 and diagrammatically indicated in Fig. 3^a, the parts n , o , b' correspond to the parts g , i and b of the first described modification with the exception that the conduit j is missing. The jet n which is advantageously used as a main jet is located in relation to the nozzle b' and this jet has an air inlet o and is advantageously of the submerged type, as indicated in Fig. 3. The air inlet o is, at the upper extremity, equipped with a nipple 5 so as to restrict the inlet opening. A second conduit 10 independent of the first system then extends from the source of supply to a jet g , which communicates with an open top well i' . From this open top well i' a conduit 11 extends to a jet k , which communicates with an air inlet chamber m , constructed similar to the air inlet o . A conduit l leads from the space above the jet k to the main air passage of the carburetor, where fuel is fed through the orifice f .

From the foregoing it is obvious that two means of feeding fuel are provided independently from one another; one comprising the parts n , o , b' and directly communicating with the supply, and the other embracing the elements g , k , m , l and f and also connected to the supply. By virtue of the fact that the open top well i' has not a restricted inlet opening, the jet g feeds fuel independent of the suction existing in the main air passage and cannot deliver more than a constant quantity of fuel at unit time determined by the size of orifice of jet g . But beyond this jet the air inlet m with the constricted inlet opening is provided and as a result of the presence of this air inlet m the orifice f does not necessarily take all of the fuel admitted to the valve e as the suction is partly neutralized by the restricted opening in the inlet m . Under certain conditions it may take all of this fuel, but under other conditions it takes a less quantity. The delivery system f is thus a nozzle which is variable per unit time, but which has a predetermined maximum delivery for it cannot take more than will flow from the jet g per unit time. When it has taken less than will flow per unit of time it may take a quantity which varies per unit of time to any extent ranging between zero and the maximum defined for a gravity delivery at g . During the period in which f is taking the available fuel, the flow at g would be constant per unit of time. But so long as the delivery at f is less than a maximum of which the nozzle g is capable, then neither the delivery at f or at g is constant per unit time because the excess delivery at g over that delivered at f accumulates in the unre-

stricted air inlet i' and until it arrives there-
in to a level corresponding to that of the
liquid in the supply. Having arrived at
this level if the delivery from f still con-
tinues to be less than that of which g is
capable, then g only delivers to keep the
level in the well i' the same as that in the
supply, so that under these conditions the
flow through the delivery jet g is not con-
stant per unit time. Attention is called to
the fact that the main jet u , the restricted
air inlet conduit o and the nozzle b are not
subjected to the entire suction effect of the
engine, but the suction effect is moderated
by the partial atmospheric vent provided
for by the air inlet conduit o .

In a further modified embodiment of the
invention, as shown in Fig. 4 and diagram-
matically indicated in Fig. 4^a, the main and
pilot jets are entirely in series. Between
the first jet g' and the second jet k pro-
vision is made whereby a certain head of
liquid has to accumulate above the first jet
before it is accessible to the second jet. As
shown, a nipple p is interposed so that be-
fore the fuel is available for the pilot jet
 k it has, after issuing from the jet g' , to
rise to a head corresponding with the top of
the nipple p . This head reduces the gravity
flow from the float chamber under the head
occurring in the float chamber. By inter-
changing the nipple p with one having a
lower or higher top the rate of gravity flow
from the jet g' per unit time may be modi-
fied as required in connection with the pilot
jet k without affecting the delivery from the
jet g' for the main nozzle b . The jet g'
communicates with the space below the nip-
ple p and the nipple is disposed with its
axis arranged vertically, whereby the liquid
fuel rises in the nipple and flows by gravity
from the top thereof into a chamber which
is in communication with the port j' of the
series passage communicating with the sec-
ond of the jets which are in series. The
first jet g' of the series is utilized as a
main jet, for which purpose it is placed to
feed to the fuel delivery orifice b and is
provided with a conduit having a restricted
air inlet i^2 . The conduit communicates with
the chamber above the interchangeable nip-
ple p and is in communication with the main
jet through the conduit in the nipple, the
chamber below, the nipple and a conduit j'
between such chamber last mentioned and
the space above the main or first jet of the
series. The second or pilot jet k is the
same as described in connection with Figs.
1 and 2.

The liquid fuel, when the throttle is open,
flows through the jet g' and issues through
the main nozzle b into the main air pas-
sage of the carburetor. When, however,
the throttle is partially closed, the fuel must
first rise until it reaches the top edge of

the nipple p and may then flow through
the port j^2 to the jet k , which is in commun-
ication with a restricted air inlet. It there-
fore follows that the action of this car-
buretor is identical with the action of the
modification described in Figs. 1, 2 and 3^a,
ensuring thereby a variable delivery of fuel
per unit time both for the main jet and the
pilot jet by virtue of the provision of the
air inlets having a restricted opening at
the upper extremity.

In a still further modified embodiment of
the invention, shown in Fig. 5 and dia-
grammatically indicated in Fig. 5^a, a
further jet q' is arranged in the series. This jet puts a maximum limitation upon
the amount of fuel delivered per unit time
by the carburetor. This jet may be disposed
in the means of communication between the
float chamber or other source of supply and
a space below the first jet g^2 . An air inlet r
is provided in connection with the initial jet
 q' and as the air inlet is unrestricted the
initial jet is entirely relieved from the suc-
tion effort of the engine acting, as stated be-
fore, and giving a constant maximum
quantity of liquid per unit time. The dis-
charge from the jet q' may be modified by
employing in place of the jets g^2 other jets
 g^3 or g^4 (Fig. 6) of differing heights on the
same principle as described in connection
with nipple p in the modification shown in
Fig. 4. The engine may use the full
capacity of the jet Q' , or any less amount,
in which case fuel accumulates in the air
inlet r appertaining to the initial jet and
the first jet g^2 , which is disposed below
the level of liquid fuel in the supply and
located in relation to a fuel delivery orifice
 b^2 is fed from the liquid fuel which is ac-
cumulated above the initial jet. The pilot
jet k' is advantageously disposed level with
or above the liquid fuel in the supply so that
it is not submerged. By the employment of
the above mentioned initial jet q' which is
of particular advantage in connection with
large carburetors, it is impossible even by
tampering with the above mentioned jet g^2
or with the choke, or in fact with any part
of the carburetor other than the initial jet
to enable the carburetor to give more than
the predetermined amount of fuel as defined
by the size of the initial jet.

The above mentioned first jet g^2 is of such
size or capacity as to give the desired
amount of fuel under the influence of the
suction effort of the engine and the liquid
fuel for supplying the pilot jet k' will then
issue by gravity from said first jet. If the
bore of the first jet should be such that more
or less fuel issues than is required for the
pilot jet, this may be corrected without
altering the capacity of the first jet by alter-
ing the head under which the fuel flows
from the first jet. This may be obtained by

substituting jets g^3 or g^4 of differing heights (Fig. 6) for the first jet.

In all the embodiments of the invention, the first jet g' or g^2 is in communication with a nozzle b by which it is in direct communication with the main air passage of the carburetor. This opening functions as an unrestricted air inlet when the pilot jet k or k' is in use, so that, as described in connection with the initial jet in Figs. 5 and 5^a, the first jet g , g' , or g^2 determines the maximum amount of fuel which is supplied to the pilot jet k or k' . The nozzle b or b^2 is thus adapted to function as an air conduit 15 when the pilot jets k or k' are in use. It is therefore unnecessary to unduly restrict the pilot jet when the latter is level with or above the level of the liquid fuel in the float chamber and a suitable space k^2 is provided 20 below the latter in which liquid fuel may accumulate to be used in starting. The pilot jet may be fed through a conduit k^3 extending nearly to the bottom of this space, so that the contained fuel may be readily 25 extracted.

While the drawings disclose preferred embodiments of the invention, I do not wish to be limited to the exact constructional features as shown but want to include all modifications constituting departures within the scope of the invention as defined by the appended claims.

I claim:

1. In a carburetor for an internal combustion engine, a jet disposed below the normal

liquid level in the supply, an air inlet insufficient to neutralize the effect of the engine suction upon said jet communicating with the space above said jet, a second jet, a conduit establishing a series communication with the space above said first jet and the space below said second jet, a separate and independent air inlet communicating with the space above said second jet, and a conduit adapted to receive air and deliver to the main air passage of the carburetor in conjunction with said air the whole of the fuel received by the carburetor which is not delivered by said second jet.

2. In a carburetor, a well, means below the normal liquid level in the supply to supply fuel to said well, a restricted air inlet to the space in said well above said fuel supply means; a second well having a restricted air inlet at its upper portion, a conduit connecting the lower portions of said well, a nozzle leading from said conduit at a point intermediate its ends and arranged to discharge into the carburetting chamber and a second conduit leading from the lower portion of the second well to the said chamber, said first named conduit being thereby adapted to receive air and to deliver to the carburetting chamber, in conjunction with such air, all of the fuel received by the carburetor which is not delivered by the first named conduit through the second well.

In witness whereof I have hereunto set my hand.

CLEMENT BROWN.
